GAME BOARD

Robert D. St. Cyr and Jay O. Such, Leominster, and
Richard C. Adams, Hudson, Mass. (all of 54 Washington
St., Leominster, Mass. 01453)

Filed Oct. 15, 1974, Ser. No. 514,770

Term of patent 14 years

Int. Cl. D21—01

U.S. Cl. D34—5 SS

FIG. 1 is a perspective view of a game board showing our new design:

FIG. 2 is a plan view of the lower left-hand quadrant of the board shown in FIG. 1;

FIG. 3 is a diagrammatic view of the relationship of FIG. 2 to FIG. 1;

FIG. 4 is a plan view of the lower right-hand quadrant of the board shown in FIG. 1;

FIG. 5 is a diagrammatic view of the relationship of FIG. 4 to FIG. 1;

FIG. 6 is a plan view of the upper right-hand quadrant of the board shown in FIG. 1;

FIG. 7 is a diagrammatic view of the relationship between FIG. 6 and FIG. 1;

FIG. 8 is a plan view of the upper left-hand quadrant of the board shown in FIG. 1; and

FIG. 9 is a diagrammatic view of the relationship between FIG. 8 and FIG. 1.

We claim:

The ornamental design for a game board, as shown.
